ABSTRACT: A range hood structure including an air intake and an exhaust outlet opening to the exterior of an enclosure in which the hood is installed. The hood structure includes an air pump for pumping air therethrough and has been modified to include a manually operable exhaust outlet closure baffle as well as a selectively openable supplemental exhaust outlet opening into the interior of the enclosure in which the hood is installed for circulation of air within the enclosure.

AIR CIRCULATING STOVE HOOD

The air circulating stove hood of the instant invention has been designed primarily for use in camper bodies, camper trailers, house trailer bodies and houseboat bodies although it is to be understood that the air circulating stove hood may also be useful in other environments.

When enclosures such as the above-mentioned body structures are provided with range or stove hoods for exhausting cooking odors and fumes to the exterior of the enclosure, the air within the enclosure may be changed by operation of the blower assembly of the stove hood as the cooking gases are exhausted if a window or door of the enclosure is opened. However, it is sometimes desired to circulate air within such an enclosure without exhausting appreciable quantities of air from within the enclosure and thus necessitating the intake of fresh air from the exterior of the enclosure to replace the air which has been exhausted.

As an example, if the enclosure is being utilized in the summertime and if provided with an air conditioner, the galley or kitchen area of the enclosure may be disposed somewhat remote from the air conditioner with the result that air is not circulated within the galley area. In addition, an enclosure being utilized during the winter months may be provided with heating means which is remote from the galley area and warm air may not be properly circulated through the galley area.

It is accordingly the main object of this invention to provide a range hood operable to exhaust cooking gases and heat to the exterior of an enclosure within which a stove or range is disposed and including means by which the range or stove hood may be utilized to circulate air within the enclosure immediately adjacent the hood.

Another object of this invention is to provide a range or stove hood in accordance with the preceding object and which may be in the form of a conventional form of range or stove hood which has been only slightly modified so as to also be adapted for circulating air adjacent the hood as well as exhausting heat and cooking fumes from above the associated stove or range.

A still further object of this invention is to provide a range hood in accordance with the preceding objects and including readily operable controls whereby the hood may be readily converted from cooking gas exhausting operation to an operation of circulating the air within the associated enclosure.

A final object of this invention to be specifically enumerated herein is to provide a stove hood in accordance with the preceding objects which will conform to conventional forms of manufacture, be of simple construction and easy to use so as to provide a device that will be economically feasible, long lasting and relatively trouble-free in operation.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

FIG. 1 is a perspective view of the interior of a pickup truck camper body illustrating a hood constructed in accordance with the present invention positioned over a range top;

FIG. 2 is a perspective view of one rear side portion of the camper body illustrating the shield over the outlet for the gases exhausted by the stove hood;

FIG. 3 is an enlarged fragmentary transverse vertical sectional view taken substantially upon the plane indicated by the section line 3-3 of FIG. 1;

FIG. 4 is a horizontal sectional view taken substantially upon the plane indicated by the section line 4-4 of FIG. 3;

FIG. 5 is a longitudinal vertical sectional view taken substantially upon the plane indicated by the section line 5-5 of FIG. 4; and

FIG. 6 is a perspective view of an L-shaped plate utilized to convert a conventional stove hood into an air circulating hood constructed in accordance with the present invention.

Referring now more specifically to the drawings, the numeral 10 generally designates a pickup truck including a load bed 12 upon which a camper body referred to in general by the reference numeral 14 is mounted. The camper body 14 includes a side wall 16 having an opening 18 formed therethrough.

A range hood assembly generally referred to by the reference numeral 18 is provided and includes a hood assembly referred to in general by the reference numeral 20. The hood assembly includes upstanding front and rear walls 22 and 24 as well as opposite walls 26 and 28 interconnected by a top wall 30. A generally rectangular housing referred to in general by the reference numeral 32 is disposed within the assembly 20 and includes a front wall 33 and opposite sidewalls 34 and 36, the rear wall of the housing 32 being eliminated to form an outlet opening registered with the exhaust outlet opening 38 formed in the rear wall 24 into which the inner end of a sleeve secured through the sidewall 16 projects. The housing 32 includes a bottom wall 42 through which the inlet end of an intake shroud or sleeve 44 is secured and the outlet end of the intake shroud or sleeve 44 embraces the fan blades 46 which are mounted on the output shaft of an electric motor 48 supported from the underside of the top wall 30. The fan blades 46 and motor 48 comprise air pump means for pumping air through the assembly 18 and exhausting the pumped air to the exterior of the camper body or enclosure 14.

A shield 50 is mounted over the outlet end of the sleeve 40 to prevent rain or snow from entering the outlet end of the sleeve 40 and a hinged closure flap or valve member 60 is hingedly supported from the outlet end of the sleeve 40 by means of a hinge structure 62 and is normally gravity urged to the closed position illustrated by the phantom lines 64 closing the outlet end of the sleeve 40.

It is to be understood that the immediately preceding detailed description of the assembly 18 refers to a conventional form of range hood assembly which may be found in various types of camping enclosures such as the camper body 14.

In order to convert the assembly 18 for circulating air within the enclosure 14 in accordance with the present invention, a bowden cable assembly referred to in general by the reference numeral 68 is connected between the closure flap or valve member 60 and the front wall 22 of the hood assembly 20 and provided with a manually engageable knob 70 disposed forwardly of the upper portion of the front wall 22 whereby the flap valve member 60 may be readily manually shifted between the open and closed positions illustrated in solid and phantom lines, respectively, in FIG. 3 of the drawings. In addition, an opening 72 is cut in the sidewall 34 and a pair of openings 74 are cut in the sidewall 26. Further, a pair of closure doors 76 are hingedly supported upon the exterior of the sidewall 26 for swinging between the open and closed positions illustrated in phantom and solid lines, respectively. The doors 76 are supported from the sidewall 26 by means of hinge assemblies 78 which serve to lightly frictionally resist swinging movement of the doors 76 and each of the doors 76 is provided with a latch 80 for securing the corresponding door 76 in the closed position. In addition, when converting the range hood assembly 18 into a hood assembly which may be also utilized to circulate air within the enclosure or camper body 14, an L-shaped panel structure referred to in general by the reference numeral 82 is provided and includes an upstanding leg 84 and a horizontal leg 86. The panel structure 82 is secured, in any convenient manner, between the sidewalls 26 and 34 with the upper end of the upstanding leg 84 secured to the portion of the top wall 30 extending between the front walls 32 and 22. Further, the end of the leg 86 remote from the leg 84 is secured to the lower marginal portion of that portion of the rear wall 24 extending between the walls 26 and 34. Accordingly, that area between the leg 84 and the rear wall 24 and between the sidewalls 26 and 34 above the horizontal leg 86 is completely enclosed and the openings 72 and 74 open into the opposite sides of this area.

Of course, when the range hood assembly 18 is to be utilized in the conventional manner, the doors 76 are closed and the flap valve member 60 is opened. In this manner, operation of the motor 48 will cause air from immediately below the range hood assembly 18 to be pumped through the housing 32 and out the exhaust sleeve 40. However, when it is desired to circulate air within the enclosure, the bowden cable assembly 68 is actuated to close the flap valve member 60 and either one or both of the doors 76 may be opened. Then, operation of the motor 48 will cause air to be drawn upwardly into the range hood assembly 18 and to be exhausted horizontally therefrom through the openings 74.

It may of course be appreciated from the above description that the conventional range hood assembly 18 may be readily modified in accordance with the present invention. Further, the necessary components to complete the conversion are relatively inexpensive. Also, conversion of the range hood assembly 18 may include the provision of peripheral seals secured to the sidewall 26 about the openings 74 against which the inner surfaces of the doors 76 may seal when closed in order to prevent any leakage of greasy cooking fumes outwardly through the openings 74. Further, any suitable means may be utilized to form the necessary openings in the sidewalls 26 and 34 during conversion of the range hood assembly 18 and any suitable means may be utilized to secure the panel structure 82 in position.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention.

What we claim as new is as follows:

1. In combination with an enclosure, a combined circulation and exhaust assembly mounted within said enclosure and including a range hood including upstanding peripheral walls defining a downwardly opening recess for positioning above a stove or range, said assembly also including a fan housing disposed within said hood and including a downwardly opening inlet and an outlet opening to the exterior of said enclosure, a fan structure in said housing for pumping air therethrough, a first manually operable valve associated with said outlet for the selectively closing the latter, one of said hood walls including an outlet opening formed therein opening into the interior of said enclosure, said housing including an outlet opening communicated with said hood outlet opening, and a second manually operable valve associated with said hood outlet opening for selectively opening and closing the latter, said housing and hood outlet openings being formed in spaced opposing upstanding peripheral walls of said hood and housing, respectively, said hood including a sidewall portion extending between one pair of corresponding ends of said opposing walls and an upper wall portion extending between the upper marginal edge portions of said opposing walls, and an L-shaped panel including upstanding and horizontal legs and supported between said opposing walls with the upstanding leg of said panel of said sidewall portion and extending upwardly from said horizontal leg to said upper wall portion and said horizontal leg extending from said upstanding leg to said upstanding wall portion and spanning the spacing between the lower marginal edges of said opposing walls to form a closed passage extending between said housing and hood outlet openings.

2. The combination of claim 1 wherein said second manually operable valve comprises a swingable closure door

supported from the peripheral wall of said hood in which the hood peripheral wall outlet opening is formed.

3. The combination of claim 2 wherein said closure door is swingably supported from said hood for swinging in a generally horizontal plane by a hinge structure including means lightly frictionally resisting swinging movement of said door relative to said hood.

4. The combination of claim 1 including a manually actuatable remote control for said first valve, said remote control comprising a bowden cable assembly.

5. In combination with an enclosure, a combined circulation and exhaust assembly mounted within said enclosure and including an air intake and a first exhaust outlet opening to the exterior of said enclosure, said assembly including a second supplemental exhaust outlet opening into the interior of said enclosure, air pump means in said assembly for pumping air therethrough from said inlet to said first and second outlets, said outlets including first and second valve members, respectively, for selectively opening and closing said outlets, said second valve member comprising a swingable closure door supported from the exterior of said assembly.

6. The combination of claim 5 wherein said closure door is swingably supported from said assembly for swinging in a generally horizontal plane by a hinge structure including means lightly frictionally resisting swinging movement of said door relative to said assembly.

7. The combination of claim 5 wherein said assembly includes a downwardly opening stove hood including upstanding front, rear and opposite side peripheral wall portions interconnected at their upper marginal portions by means of a top wall, a downwardly opening housing disposed within said hood and including upstanding front, rear and opposite side panel portions, said first exhaust outlet opening through said rear wall portion, said air pump means being disposed within said housing, one pair of corresponding sidewall and panel portions having aligned openings formed therethrough defining opposite end portions of said second exhaust outlet, said valve member being supported from the last-mentioned sidewall portion, and an L-shaped panel secured between said corresponding sidewall and panel portion enclosing the area between said corresponding sidewall and panel portions with which said aligned openings are registered.

8. In combination with an enclosure including an upstanding wall, a combined circulation and exhaust assembly mounted within said enclosure and including a range hood having interconnected upstanding peripheral walls and a top wall defining a downwardly opening recess for positioning above a stove or range with one of said peripheral walls abutted up against the inner surface of said wall of said enclosure, said wall of said enclosure including a valved outlet opening formed therethrough, said range hood having an outlet opening formed in one peripheral wall thereof registered with the outlet opening in said enclosure wall, a fan housing disposed within said hood and including an outlet registered with said outlet opening in said one peripheral wall and also a downwardly opening inlet, a second peripheral wall of said range hood being disposed generally normal to said range hood peripheral wall having said outlet opening formed therein, said housing including a wall portion horizontally spaced from and generally paralleling said second peripheral wall of said range hood and having an outlet formed therein registered with the outlet of said second peripheral wall, said hood and housing including means defining a closed air passage extending between the last two mentioned outlets, and a closure door for said outlet formed in said second peripheral wall portion.
